GAS-GUN.

1,383,111.

Specification of Letters Patent. Patented June 28, 1921.

Application filed March 18, 1918, Serial No. 223,131. Renewed September 16, 1920. Serial No. 410,744.

To all whom it may concern:

Be it known that we, GEORGE U. HALL and JAMES B. Truitt, citizens of the United States, residing at Winnemucca, in the 5 county of Humboldt and State of Nevada, have invented certain new and useful Improvements in Gas-Guns; and we do declare the following to be a full, clear, and exact description of the invention, such as 10 will enable others skilled in the art to which it appertains to make and use the same.

The principal object of our invention is to provide a highly efficient gun in which explosive gas is compressed and ignited to 15 impel the bullets from the gun by the expansive force of such gas, thus eliminating the cost of powder and cartridge cases.

A further object is to so construct the gun as to compress a large proportion of 20 the gas by spring pressure rather than compressing all by hand.

A still further object is to provide a novel arrangement of valves for controlling the passage of gas from the gas compressor to 25 the combustion chamber.

Yet another object is to so construct the gun as to permit operation thereof by the well known longitudinally slidable hand grip beneath the barrel, said grip being connected to the usual action rod.

An additional object is to provide a gun which will be comparatively simple and inexpensive, easy to operate and not liable to be injured even though roughly handled.

35 With the foregoing general objects in view, the invention resides in the novel features of construction and unique combinations of parts to be hereinafter fully described and claimed, the descriptive matter 40 being supplemented by the accompanying drawings which form a part of this specification and in which:

Figure 1 is a side elevation of the complete gun;

45 Fig. 2 is an enlarged elevation of a portion of the side opposite that shown in Fig. 1;

Fig. 3 is a top plan view of a portion of the gun shown in Fig. 2;

50 Fig. 4 is an enlarged side elevation showing the hand grip and the action rod partly retracted;

Fig. 5 is a duplicate of Fig. 4 with the exception that it illustrates the grip and action rod completely retracted and the corresponding arrangement of other parts;

Fig. 6 is a central longitudinal section of the gun showing the relative positions of parts after the hand grip and action rod have been returned to normal from the position shown in Fig. 5; 60

Fig. 7 is a side elevation showing the relative positions of the external parts when the internal features are related as shown in Fig. 6;

Fig. 8 is an enlarged side elevation with 65 parts in section on the plane of line 8-8 of Fig. 11;

Fig. 9 is a perspective view showing more particularly the relation between the action rod, the compressor operating rod, the 70 breech block retracting means, and the transmitter which opens one of the above mentioned valves upon forward movement of said operating rod;

Fig. 10 is a vertical transverse section on 75 the plane of the line 10-10 of Fig. 7;

Figs. 11 and 12 are vertical transverse sections on the planes indicated by the lines 11-11 and 12-12 of Figs. 6 and 8;

Fig. 13 is a transverse section on the plane 80 indicated by the line 13-13 of Fig. 5 showing more particularly the rock shaft and co-operating parts for opening the needle valve yet to be described;

Fig. 14 is a perspective view of a portion 85 of the rock shaft and said needle valve;

Fig. 15 is a longitudinal section through the stock of the gun;

Fig. 16 is a transverse section on the plane 90 of the line 16-16 of Fig. 15;

Fig. 17 is a detail transverse section on the plane indicated by the line 17-17 of Fig. 15 showing a lock which may be employed for holding the trigger against operation; and, 95

Fig. 18 is a perspective view of the trigger locking pin shown in Fig. 17.

In the drawings above briefly described, the numeral 1 designates the barrel of the improved gun, said barrel being suitably 100 secured to the front end of a metal case 2 in which a number of the working parts of the device are located, the rear end of said case preferably having an extension 3 into which the front end of the ordinary wooden stock 4 is inserted and secured in any preferred manner. 105

Slidably mounted in the case 2 is a tubular breech block 5 open at both its front and rear ends and decreased in diameter at said 110

front end so that an external shoulder 6 is formed at the juncture of the two diameters, the extreme front end of the block being receivable in a counterbore 7 at the breech of 5 the barrel 1. A cylindrical spark plug 8 projects snugly into the rear end of the breech block 5 and closes the same in a gas tight manner, the rear end of said plug having a head 9 threaded or otherwise suitably 10 secured in the case 2. A coiled spring 10 is located between the rear end of the breech block 5 and the head 9 for returning the former to its initial forward position after it has been retracted and released by the 15 means to be hereinafter set forth.

Any suitable type of bullet magazine 11 extends longitudinally beneath the barrel 1 and carries the usual slidable hand grip 12 which operates the several parts of the gun.

20 When this hand grip is pulled rearwardly, the breech block 5 is retracted against the tension of the spring 10 and when said block is in this retracted position, a bullet lifter 13 comes into play to raise one of the bullets

25 14 from the magazine 11 into the forward path of the breech block as will be clear from the dotted lines of Fig. 4 in connection with the full lines of Fig. 6. By the time this bullet has been thus raised, the retracting 30 means of the breech block 5 is released so that the spring 10 forces said block forwardly to position the bullet in the rear end of the barrel 1. Simultaneously with this operation, the beveled or cam shoulder 6 of 35 the breech block contacts with a portion of the bullet lifter 13 and again forces the latter to the lowered position depicted in Fig. 6. This lifter is preferably constructed as follows:

40 The lifter in question consists of an arm having one end pivoted at 15 to a suitable internal part of the case 2, the other end of said arm having a depending guard 16 which closes the rear end of the magazine 11 when 45 the lifter is raised and thus prevents the discharge of bullets from the magazine into the case 2. The upper side of arm 13 is formed with a longitudinal bullet receiving groove 17 into which the usual spring 18 of 50 the magazine 11 feeds one bullet at a time at each lowering of the lifter or arm 13. A spring 19 is employed for automatically raising the lifter 13 the moment the breech block 5 is retracted.

55 For retracting the breech block 5 and operating several of the other moving parts of the device in the manner hereinafter set forth, an action rod 20 extends rearwardly from the hand grip 12, the rear end of said 60 action rod having a shoulder 21 adapted to abut the front end of a transmitting arm 22 whose rear end is pivoted at 23 to an angular arm 24 secured to the sliding breech block 5 and extending outwardly therefrom 65 through a slot 25 in the case 2. By this ar-

rangement, a rearward pull of the hand grip 12 will shift the action rod 20 rearwardly and since this rod abuts the arm 22, the latter will transmit the motion of the former to the breech block 5, thus retracting the 70 latter against the tension of the spring 10 and permitting the bullet lifter 13 to come into play to raise one of the bullets to the position shown in dotted lines in Fig. 4. By the time the bullet has been thus placed in 75 the forward path of the breech block 5, the arm 22 strikes a fixed pin 26 and is so raised thereby as to disengage the shoulder 21, the result being that spring 10 then comes into 80 action to force the breech block 5 to its forward position, so that said block drives the bullet 14 into the breech of the barrel 1, the bullet serving at this time to seal the front end of the hollow breech block in a substantially gas tight manner. To obtain this result most effectively, the rear ends of the 85 bullets are by preference formed with rather soft lead plugs 27 which are tightly received in the reduced front end of the breech block when the bullet is forced into the barrel as 90 shown in Fig. 6.

By means of a compression cylinder 28, a piston 29 therein, and other closely associated parts yet to be described, gas is taken from a compressed gas magazine 30 in the stock 4 and further compressed into the combustion chamber within the hollow breech block. The cylinder 28 is located beneath the spark plug 8 at a slight distance in rear of the bullet lifter 13 and the piston rod 31 of piston 29 extends through a stuffing box 32 at the rear end of said cylinder, the rear end of said rod 31 extending upwardly at 33, laterally at 34 and then forwardly at 35 into the rearward path of the 105 action rod 20, so that rearward movement of said action rod will correspondingly move the piston 29. A suitable latch 36 is provided for holding the piston rod 31 in its rearmost position until said latch is released by the trigger 37 which is connected thereto by a link 38; and the moment such release takes place, a coiled spring 39 between the piston 29 and the stuffing box 32, comes into play to force said piston again 110 toward the front end of the cylinder 28. Upon each rearward movement of the piston, a charge of gas is forced from the cylinder 28 to the hollow breech block 5 and a second charge of such gas is compressed into 115 said breech block when the piston is again forced forwardly by the spring 39. For supplying the gas to the cylinder 28 and conducting such gas from this cylinder to the hollow breech block 5, the arrangement 120 of parts now to be described is provided;

A needle valve casing 40 is suitably mounted at the front end of the case 2 and the inlet 41 of this casing 40 (Figs. 8 and 11) is supplied with highly compressed gas 130

from the magazine 30 by means of a suitable tube 42. The outlet 43 of casing 40 discharges into a puppet valve casing 44 which discharges into the front end of the cylinder 28. A needle valve 45 slides within and beyond the casing 40 for controlling communication between the inlet 41 and the outlet 43 while a spring closed puppet valve 46 permits gas to be drawn into the cylinder 28 from the casing 44, but will not permit reverse movement of such gas. Valve 46 is operated by suction in the cylinder 28, but the sliding needle valve 45 is actuated mechanically from the action rod 20 by the means set forth below.

The projecting end of the needle valve 45 is provided with an adjusting nut or the like 47 (see more particularly Figs. 13 and 14) said nut engaging the lateral end of an angular link 48 which is pivoted to the lower end of a crank arm 49 on a short transverse rock shaft 50. The end of the shaft 50 opposite the arm 49, is positioned below the action rod 20 and is provided with an upstanding crank arm 51 in the rearward path of a pin 52 on the action rod. By this arrangement, rearward movement of said rod will, through the instrumentality of the parts 51, 50, 49, 48 and 47, open the needle valve 45 so that as the piston 29 is moved rearwardly by the continued rearward movement of said action rod, a charge of gas will be drawn from the magazine 30 through the tube 42 and the needle valve casing 40 into the puppet valve casing 44, and from the latter into the cylinder 28. When the piston reaches the limit of its rearward travel, the latch 36 comes into play to hold it against forward movement until the trigger 37 is released, and it may here be said that during the rearward movement of said piston, it not only draws a charge of gas into the front end of cylinder 28, but forces a previously intaken charge from the rear end of said cylinder into the breech block 5 by the following means.

A tube 53 (see more particularly Fig. 8) leads from the rear end of the cylinder 28 to a three-way check valve casing 54 (Figs. 8, 11 and 12). The casing 54 communicates with the interior of the sliding breech block 5 by means of a port 55 in said block but a check valve 56 is provided for preventing passage of gas from said breech block back into said casing. The casing 54 also communicates at 57 (Fig. 12) with the front end of the cylinder 28. The gas compressed in the rear end of said cylinder by the rearward movement of the piston 29, is forced through the tube 53 to casing 54, through a check valve 58 in the latter and then through the check valve 56 and port 55 into the hollow breech block 5. When piston 29 is released and spring 39

forces it forwardly, the gas compressed by such movement of the piston, leaves the front end of the cylinder 28 by way of the port 57 and thus enters the casing 54. In this casing, the compressed gas passes 70 through the third check valve 59 and then through valve 56 and port 55 into the hollow breech block 5. Two charges of gas having been compressed in this breech block by the rearward and forward strokes 75 of the piston, this gas is fired by the spark plug 8 in a manner to be set forth, with the result that the bullet is projected from the barrel 1.

As the piston 29 moves forwardly, it is 80 necessary that it shall draw in a new charge of gas into the rear end of cylinder 28 and for obtaining this result, means are provided for again opening the needle valve 45 to admit gas from the magazine 30 to the 85 puppet valve casing 44 and from this casing a tube 60 leads to the rear end of the cylinder 28 and discharges into the latter through a check valve 61. The valve opening means is by preference constructed as follows: 90

A longitudinal transmitting arm 62 is pivoted to a short crank arm 63 at its front end, said crank arm depending from the rock shaft 50 above described (see Figs. 4, 5, 6, 7, 9 and 13). The rear end of the arm 95 62 is preferably off-set laterally as at 64 and disposed to be struck by the portion 35 of the piston rod 31 when the latter is moved forwardly by the spring 39. It will thus be obvious that when the portion 35 100 of said piston rod contacts with the transmission rod or arm 62, it will force forwardly on the latter and so rock the shaft 50 as to cause the crank arm 49 and link 48 to open the needle valve 45, thus permitting gas 105 to be drawn from the magazine 30 through the tube 42, casing 40, casing 44, tube 60 and check valve 61 into the rear end of the cylinder 28. The exact paths of travel of the several currents of gas having now been 110 specifically set forth, they will not be entered into in detail in the following, in order to avoid confusion.

The transmission arm 62 above briefly described, is preferably off-set downwardly at 115 its front end as shown at 65, while its rear end is provided with a suitable inclined cam 66 on its lower edge. It is the office of this cam to engage the pin 26 above described to raise rod 62 and disengage it from the piston rod 31 after said transmission rod has been moved sufficiently to accomplish its office. It is of course understood that the action rod 20 has been returned to its forward position before piston rod 31 moves 120 forwardly, this return of the action rod being effected by the usual coiled spring 67; and it may here be stated that although any other preferred means could be employed for permitting the pin 52 to pass the arm 51 130

as the action rod 20 moves forwardly, the link 48 is preferably slidable on the projecting end of the needle valve 45 against the tension of a coil spring 68 (Fig. 14). 5 By this arrangement, contact of pin 52 with arm 51 as the action rod moves forwardly will rock the shaft 50 but will not operate the needle valve 45.

As it is required that the compressed 10 charge of gas in the hollow breech block 5 shall be fired the moment the piston 29 has reached the limit of its forward movement, such movement is preferably made to close the circuit of the spark plug 8. In the present 15 showing, the vertical portion 33 of piston rod 31 strikes a contact spring 69 on and insulated from the rear end of the cylinder 28 and thus completes the circuit of the spark plug, the current being supplied from 20 a battery 70 and spark coil 71 through suitable wiring 71' said battery and coil being located in appropriate pockets formed in the stock 4 as featured in Figs. 15 and 16. In order to prevent wasting of the current 25 from the battery 70 by continued contact of the parts 33 and 69 after closing of the spark plug circuit, a shock absorbing spring 72 is located at the front end of cylinder 28, and it is the office of this spring to cause a 30 slight recoil or rebound of the piston 29 when struck by the latter, so that the part 33 of the piston rod 31 will be moved rearwardly to a sufficient extent to clear the contact 69.

35 As a preferred type of the gas magazine 30, we have shown such magazine in the form of a tube open at its front end and having at its rear end an integral cap 73 which is threaded into the rear end of a 40 tubular casing 74, said casing being inset in the stock 4 and opening through the rear end of the latter. The front end of casing 74 may be reduced at 75 and communicate with tube 42 or any other preferred 45 construction could well be employed. At 50 76, the tubular casing 74 is formed with a filling opening located near its rear end and normally closed by a plug or any other preferred means 77 (Fig. 16). The tubular 55 magazine 30 normally closes the opening 76 as shown, but when the cap 73 is unthreaded and said magazine pulled rearwardly to a sufficient extent, this opening will be exposed. By removing the plug 77, 60 suitable gas may now be compressed in the magazine, after which the tube 30 is again moved into casing 74 and held by threading the cap 73 into place. To prevent possible leakage of gas from the interior of the 65 tubular magazine 30 between said magazine and the casing 74, a packing 78 is preferably provided on the front end of said magazine. Also, although in some cases the mere suction from the cylinder 28 could be relied 70 upon to draw the gas from the magazine,

75 a follower 79 is preferably located in the latter and provided with a spring 80 for moving it forwardly as the gas is expelled. It is to be understood, however, that due to the short period of time which the needle 70 valve 45 is open, only a small quantity of gas will be drawn from the magazine and due to the high compression of this gas, such a quantity will be ample. It may further be stated that sufficient air is mixed 75 with the incoming gas to insure a highly combustible mixture, by forming air inlet openings 44' in the puppet valve casing 44 through which all charges of gas are drawn before entering the cylinder 28. 80

85 Preferably used in connection with the features above described, is a transversely slidable locking pin 81 for the trigger 37, said pin having a notch 82 which will permit rearward movement of said trigger when positioned in rear of the latter, but when the pin is so shifted as to dispose said notch out of alignment with the trigger, the latter cannot be operated to release the latch 36 and consequently the gun cannot be fired. 90 A spring pressed detent 83 operating in a zigzag groove 84 in the pin 81 may be employed for holding the latter in either of its two positions, but other means could well be employed for this purpose if desired. 95

100 Another feature which will in most cases be embodied in the invention, is a knob 85 carried by the front end of the forwardly extending portion 35 of the piston rod 31, so that the piston 29 may be operated by hand to initially expel accumulated air from the gun and charge the same with an explosive mixture. As shown in the drawings, this knob is located on the exterior of one of a pair of removable side 105 plates 86 which are employed for housing as many of the external parts of the gun as possible.

110 The operation of the improved gun is as follows:

Assuming that the parts stand as seen in Fig. 7 except that the piston 29 has been moved forwardly by the spring 39, and that the bullet 14 last deposited in the barrel 1 has been fired therefrom, a rearward pull 115 on the hand grip 12 will shift the action rod 20 rearwardly, thus causing the transmission arm 22 which then abuts the shoulder 21 as seen in Fig. 7, to retract the hollow breech block 5 against the tension of the 120 spring 10 (see Fig. 9). Upon this retraction, the bullet lifter 13 positions the bullet in advance of the breech block as shown in dotted lines in Fig. 4 and the moment this bullet has been so raised, the pin 26 shifts the 125 transmission arm 22 (see Fig. 4) so that spring 10 immediately returns the hollow breech block 5 to its forward position and forces the bullet 14 into the rear end of the 130 barrel, (see Fig. 6) simultaneously lowering

the lifter 13. Continued rearward movement of the action rod 20 opens the needle valve 45 by the means above described and through the instrumentality of the piston rod 31, moves the piston 29 rearwardly. This movement of the piston forces the gas from the rear end of the cylinder 28 into the hollow breech block 5 through the communicating means above set forth for this purpose and simultaneously a new charge of gas and air is drawn into the front end of the cylinder. The latch 36 holds the piston in a retracted position against the tension of the spring 39 and when the hand grip 12 is returned to its forward position, the rock shaft 50 is operated idly. Pulling of the trigger 37 will now release the latch 36 so that spring 39 will suddenly force the piston 29 forwardly, thus driving the charge of gas and air from the front end of cylinder 38 into the hollow breech block 5 and at the same time drawing a new charge of gas and air into said cylinder behind the piston, the valve 45 being opened in the meantime by 25 the transmission rod 62 for this purpose. When the vertical portion 33 of the piston rod 31 strikes the contact 69, the circuit of the spark plug 8 is instantly completed so that a spark will jump between the two terminals of the plug, thus firing the highly compressed charge in the breech block, with the result that the bullet will be impelled from the barrel 1. The spring 72 serves to bring piston 29 to a standstill and also to 30 cause sufficient recoil of this piston to separate the portion 33 of its rod 31 from the contact 69, thus breaking the circuit of the spark plug and preventing the unnecessary use of current from the battery 70. When 35 the part 33 of the rod 31 strikes the contact 69, the current flows from the coil 71 to the central electrode of the spark plug 8, jumps across the gap between the two electrodes of the plug to the metallic shell of the latter, from said shell to the cylinder 28, from 40 this cylinder to the piston 29, from the piston along the rod 31 and from this rod to the contact 69, from which it returns to the coil through the other wire 71.

45 From the foregoing, taken in connection with the accompanying drawings, it will be obvious that although our improved gun is of comparatively simple and inexpensive nature, it will be highly efficient and durable 50 and will operate with ease and with less expense than those employing powder contained in cartridge cases provided at their front ends with the bullets. The operation of the several parts is sufficiently sensitive 55 to insure the best results, yet the gun will stand considerable rough usage without injury. For these and other obvious reasons, the invention is particularly well adapted for military use, although it is to be understood 60 that the invention is not restricted to 65 any particular field. Since probably the best results are obtained from the several features shown and described, these features are by preference employed, but within the scope of the invention as claimed, numerous minor changes may well be made.

We claim:

1. In a gas gun, the combination of a barrel, a sliding tubular breech block at the rear end of said barrel and having an open front end communicating therewith, a compressor independent of said breech block for forcing compressed gas into said block, a gas supply means for said compressor, means for shifting said breech block rearwardly from the barrel and then again forwardly and for actuating said compressor to compress gas in the breech block when said breech block has reached its forward position, communicating means between said compressor and the interior of said breech block, means for placing a bullet at the rear end of the barrel each time said block is retracted, and means for igniting the compressed gas in said breech block. 70
2. In a gas gun, the combination of a barrel, a fixed spark plug spaced in rear of said barrel and aligned therewith, a tubular breech block slidably surrounding said spark plug at its rear end and communicating at its front end with said barrel, a compressor for forcing compressed gas into said breech block, a gas supply for said compressor, communicating means between said compressor and the interior of said breech block, means for shifting said block rearwardly from the barrel and then again forwardly and for operating said compressor to compress gas in the breech block when the latter has reached its forward position, means for placing a bullet at the rear end of the barrel each time said breech block is retracted, and means for completing the circuit of said spark plug after compression of the gas in said breech block. 90
3. In a gas gun, the combination of a barrel, a sliding hollow breech block at the rear end of said barrel, a compressor for forcing compressed gas into said breech block, communicating means between said compressor and said block, gas supply means for said compressor, a sliding operating rod for said compressor, a sliding action rod for shifting said operating rod when moved rearwardly, transmitting means for imparting motion to said breech block from said action rod to retract the former, means for placing a bullet at the breech of the barrel when said breech block is retracted, means for releasing said transmitting means after placing 105 of the bullet, a spring for returning said breech block to its forward position when said transmitting means is released, and means for firing the charge of gas forced into the breech block by said compressor. 110
4. In a gas gun, the combination of a barrel, a sliding tubular breech block at the rear end of said barrel and having an open front end communicating therewith, a compressor independent of said breech block for forcing compressed gas into said block, a gas supply means for said compressor, means for shifting said breech block rearwardly from the barrel and then again forwardly and for actuating said compressor to compress gas in the breech block when said breech block has reached its forward position, communicating means between said compressor and the interior of said breech block, means for placing a bullet at the rear end of the barrel each time said block is retracted, and means for igniting the compressed gas in said breech block. 115
5. In a gas gun, the combination of a barrel, a sliding tubular breech block at the rear end of said barrel and having an open front end communicating therewith, a compressor independent of said breech block for forcing compressed gas into said block, a gas supply means for said compressor, means for shifting said breech block rearwardly from the barrel and then again forwardly and for actuating said compressor to compress gas in the breech block when said breech block has reached its forward position, communicating means between said compressor and the interior of said breech block, means for placing a bullet at the rear end of the barrel each time said block is retracted, and means for igniting the compressed gas in said breech block. 120
6. In a gas gun, the combination of a barrel, a sliding tubular breech block at the rear end of said barrel and having an open front end communicating therewith, a compressor independent of said breech block for forcing compressed gas into said block, a gas supply means for said compressor, means for shifting said breech block rearwardly from the barrel and then again forwardly and for actuating said compressor to compress gas in the breech block when said breech block has reached its forward position, communicating means between said compressor and the interior of said breech block, means for placing a bullet at the rear end of the barrel each time said block is retracted, and means for igniting the compressed gas in said breech block. 125
7. In a gas gun, the combination of a barrel, a sliding tubular breech block at the rear end of said barrel and having an open front end communicating therewith, a compressor independent of said breech block for forcing compressed gas into said block, a gas supply means for said compressor, means for shifting said breech block rearwardly from the barrel and then again forwardly and for actuating said compressor to compress gas in the breech block when said breech block has reached its forward position, communicating means between said compressor and the interior of said breech block, means for placing a bullet at the rear end of the barrel each time said block is retracted, and means for igniting the compressed gas in said breech block. 130

4. A structure as specified in claim 3, said transmitting means comprising an arm pivoted to said breech block and a shoulder on said action rod engaged by said arm, and 5 said releasing means consisting of a projection in the path of said arm for shifting it from engagement with said shoulder.

5. In a gas gun, the combination of a barrel and means for feeding bullets to its 10 breech, a combustion chamber at said breech, a compression cylinder and gas supply means therefor, communicating means between said cylinder and said gas supply means including a valve, communicating 15 means between said cylinder and said combustion chamber, a piston in said cylinder for forcing compressed gas into said combustion chamber, an operating rod for said piston, an action rod for actuating said operating rod, means operated by said action 20 rod for operating said valve to control the passage of gas to said cylinder, and means for firing the gas charge in said combustion chamber.

6. In a gas gun, the combination of a barrel and means for feeding bullets to its breech, a combustion chamber at said breech, a compression cylinder and gas supply means therefor, communicating means between said cylinder and said gas supply means including a valve, communicating 30 means between said cylinder and said combustion chamber, a piston in said cylinder for forcing compressed gas into said combustion chamber, an operating rod for said piston, a longitudinally slidable action rod for moving said operating rod rearwardly to correspondingly shift said piston to force 35 a charge of gas into the combustion chamber, means operated by rearward movement of 40 said action rod for opening said valve to permit gas from said gas supply means to enter the front end of said cylinder, trigger released means for holding said piston 45 against return to the front end of the cylinder, a spring for moving said piston forwardly upon release of said holding means to force a second charge of gas into said 50 combustion chamber, transmitting means actuated by forward movement of said piston for again operating said valve opening means to admit additional gas from the gas supply means into the rear end of the compression cylinder, and means for firing the 55 gas in said combustion chamber.

7. A structure as specified in claim 6, said transmitting means consisting of an arm pivoted to said valve opening means and disposed in the forward path of said piston 60 operating rod, and a projection in the path of said arm for shifting it from engagement with said operating rod.

8. In a gas gun, the combination of a barrel, a hollow sliding breech block at the 65 rear end of said barrel, a longitudinally slid-

able action rod, transmitting means for moving said breech block rearwardly upon rearward movement of said action rod, means for placing a bullet at the breech of the barrel while said breech block is retracted, means for releasing said transmitting means after placing of the bullet, and a spring for then returning said breech block to its forward position; together with a compression cylinder, gas supply means 70 for said cylinder, communicating means between said cylinder and said gas supply means including a valve, a double acting piston in said cylinder for forcing compressed gas into said breech block, an operating rod 75 for said piston shifted rearwardly by rearward shifting of said action rod to correspondingly move said piston and force a charge of gas into said breech block, means actuated by said rearward shifting of said 80 action rod for opening said valve to admit gas into the front end of said cylinder, trigger released means for holding said piston at the rear end of the cylinder, a spring 85 for forcing said piston forwardly when said holding means is released whereby to force another charge of gas into said breech block, additional transmitting means for again operating said valve opening means as said piston moves forwardly to supply gas to 90 the rear end of said cylinder, and means for firing the compressed gas forced into said breech block.

9. A structure as specified in claim 8, said first-named transmitting means comprising 100 an arm pivoted to said breech block and a shoulder on said action rod engaging said arm; said second-named transmitting means comprising an arm pivoted to said valve opening means and disposed in the forward path of said piston operating rod; and said 105 releasing means for said first named transmitting means consisting of a projection in the paths of both of said arms for swinging them to inoperative position after their 110 proper periods of operation.

10. In a gas gun, the combination of a barrel and means for feeding bullets to its breech, a combustion chamber at said breech, a compression cylinder, gas supply 115 means for said cylinder, communicating means between said cylinder and said combustion chamber, a piston in said cylinder for forcing compressed gas therefrom into said combustion chamber, a spring for shifting said piston from one end of the cylinder to the other, an electric ignition device for said combustion chamber, circuit closing means for said ignition device including a fixed contact and a second contact movable 120 with said piston to engage said first named contact at the completion of the piston stroke, and means for producing recoil of said piston at the end of its stroke, whereby 125 to again disengage said contacts.

11. In a gas gun, a stock and a barrel suitably connected, gas compressing and firing means for impelling bullets from the barrel, and gas supply means for said compressing means comprising a tubular casing in the stock and opening through the butt thereof, said casing having between its ends a filling opening, a tubular gas magazine slidable tightly in said casing and open at 10 its inner but closed at its outer end, and releasable means for holding said magazine in said casing but permitting sufficient withdrawal thereof to expose said filling opening.
12. A gun comprising a barrel having at its breech a combustion chamber, means for feeding bullets into said breech, a fuel reservoir, means for charging said combustion chamber from said reservoir, and a common 20 operating handle for controlling both the bullet feeding means and the charging means.
13. A gun comprising a barrel having at its breech a combustion chamber, means for feeding bullets into said breech, a fuel reservoir, means for charging said combustion chamber from said reservoir, and a common 25
14. A gun comprising a barrel having at its breech a combustion chamber, a bullet magazine, a bullet lifter for feeding bullets from said magazine into said breech, a slide for controlling the operation of said bullet lifter, a fuel reservoir, means including a pump operated by said slide for charging said combustion chamber, an operating member for said slide, and means for firing the charge in said combustion chamber.
15. A structure as specified in claim 13, 30 said charging means including a mixture supply tube for said combustion chamber, a valve for controlling the discharge of mixture into said chamber, and means for opening said valve after placing of the bullet at 35 the breech of the barrel.
- In testimony whereof we have hereunto set our hands in the presence of two subscribing witnesses.
